Inventor:
George W. Carver

By his Atty., J. F. Richard

UNITED STATES PATENT OFFICE.

GEORGE W. CARVER, OF EAST ORANGE, NEW JERSEY.

POCKET.

1,143,038.

Specification of Letters Patent. Patented June 15, 1915.

Application filed March 10, 1914, Serial No. 823,639. Renewed April 26, 1915. Serial No. 24,156.

To all whom it may concern:

Be it known that I, GEORGE W. CARVER, a citizen of the United States, residing in East Orange, in the county of Essex and

5 State of New Jersey, have invented certain new and useful Improvements in Pockets, of which the following is a specification.

Every mechanic feels the need of a safe, tool pocket which has no metal member to 10 hurt, which he can use as conveniently as an open pocket and which will not spill when he stoops or takes off his garment. My invention is such a pocket, and has proved fully satisfactory in use.

15 In general terms, it is a dual pocket comprising an oblong main, lower pocket stitched to the garment at the sides and bottom; and a supplemental, upper and outer pocket located above and lapped on and 20 slightly askew to the main pocket, stitched along the full length of a closed side to the main pocket and garment, across the top, and along its access side for substantially a quarter of its length; and left free and serving as a flap for the main pocket at its bottom and for three-fourths the length of its 25 access side. The free side and bottom of the supplemental pocket give convenient access to the main pocket, which is made more free 30 by cutting away, bias, the free corner of the flap.

In the drawings, Figure 1 is a front view of the dual pocket, sewed to a garment; Fig. 2 a sectional plan on the line 2—2 of Fig. 1, 35 and Fig. 3 a vertical section on the line 3—3 of Fig. 1.

The drawings illustrate a dual pocket 2 sewed to the leg 1 of a pair of breeches or overalls, and for convenience and neatness, 40 sewn at one margin into the seam 11 thereof. The dual pocket comprises a main, preferably oblong, lower, open topped pocket 20 and slightly askew thereto a supplemental, upper and outer pocket 2^a, which constitutes 45 an upward extension of and flap for the main pocket and to that end laps on it and is left free along its bottom and thence for three-fourths (or thereabout) of its height to a point 2^b along its forward or access 50 side,—that is to say, along the garment seam 11,—but is sewed to the garment along said seam above said point, across its top and down the opposite closed side, to the garment and main pocket. Sewing the supplemental pocket to the garment the full 55 length of its closed, and only a slight dis-

tance along its access side, causes the strains caused in it by use, to be bias; in which direction the elasticity of fabric is much greater than along its warp and woof.

For looks, the dual pocket is made oblong and the main pocket 20 is sewed to the garment along its far side, across its bottom, and into the garment seam 11. But for use, the pocket is made much safer if the axes 21 and 2^a of the main and supplemental pockets are somewhat askew. To attain this result without impairing the looks, the main pocket 20 is skewed by uniting it to the garment with substantially diagonally arranged 70 parallel marginal stitchings, 22 and 23.

The stitching 22 extends from a point 24 at the top of the main pocket and inward from the seam 11, say three-fourths of an inch, to said seam at substantially mid 75 height of said pocket; and the stitching 23 extends from a point at the bottom of said pocket and a like distance inward from the rearward seam, to a point in said seam substantially mid height of said pocket. The 80 stitchings of the hems are designated *h* in order that they may not be mistaken for joinings.

My pockets are made rights and lefts to suit their locations. They are especially designed for rules, gages and long hand tools. The wearers can pocket and take out such objects with a single deft motion; when the wearers stoop, and subsequently when they rise, the dual pockets will not spill; nor will 90 they when the garments are taken off, even shaken. Their safety is due to the facts:—

(a) The supplemental pocket 2^a is a true pocket extending the main pocket and when the garment is inverted acts as such, even 95 though left free along the access side. (b) Skewing the axes of the main and supplemental pockets causes long objects, 3, carried in the former to point from the access toward the closed side, as shown in dotted lines, Fig. 1, and to stand in the lower, access-side corner of the main pocket and point toward the closed side.

Rules and tools of frequent use tucked into the main pocket only partly entered under the supplemental pocket, and having an outstanding corner (as shown in full lines, Fig. 1) are as convenient as though in an ordinary pocket, but will not fall out.

Having thus described my invention, I 110 claim:—

1. Dual rule and tool pockets for and

joined to working garments, comprising a main, lower open-topped pocket, and lapped thereupon a supplemental upper and outer pocket, a portion of the cloth of said garment forming one of the walls of said pockets which wall is common to both pockets, said main lower open-topped pocket having for its outer wall a strip of cloth secured to said portion of said garment at its bottom 5 and sides but free along its top and said supplemental upper and outer pocket having for its outer wall a second strip of cloth extending partially over the top of said first mentioned strip of cloth, and secured to said 10 portion of said garment along its top, the full length along one of its sides, and only partway along the other of its sides to thereby leave an entranceway to such dual pockets.

20 2. Dual rule and tool pockets for and joined to working garments, comprising a main, lower, open-topped pocket, and lapped thereupon a supplemental upper and outer pocket, a portion of the cloth of said garment forming one of the walls of said pockets which wall is common to both pockets; said main lower open-topped pocket having for its outer wall a strip of cloth secured to said portion of said garment at its bottom 25 and sides but free along its top and said supplemental upper and outer pocket having for its outer wall a second strip of cloth having an upper side to form the top of the pocket, a long lateral side and a short lateral side both substantially at right angles to said upper side and continuing therefrom, a short lower side substantially parallel to the upper side and extending only partway from said long lateral side, and an 30 inclined side disposed between and connecting the short lower side and the short lateral side; said second strip of cloth being positioned on said portion of said garment so that its upper side is substantially parallel 35 with the lower side of said first mentioned

strip, and partially overlapping said first mentioned strip so that its lower short side will be disposed a considerable distance below the top of said first mentioned strip; and said second strip of cloth being secured 50 along its upper side and along its short lateral side to said portion of said garment, and along its long lateral side to said portion of said garment and to said first mentioned strip and said portion of said garment against which it rests.

3. Dual rule and tool pockets for and joined to working garments having a seam formed between adjacent sections and comprising a main, lower open-topped pocket, 60 and lapped thereupon a supplemental upper and outer pocket; a portion of the cloth of said garment forming one of the walls of said pockets which wall is common to both pockets, said main lower open-topped 65 pocket having for its outer wall a strip of cloth secured to said portion of said garment at its bottom, and along one of its lateral sides, its other side being secured between said adjacent sections at said seam 70 and said supplemental upper and outer pocket having for its outer wall a second strip of cloth extending partially over the top of said first mentioned strip of cloth and secured along its upper side to said portion 75 of said garment the full length along one of its lateral sides to said portion of said garment and said first mentioned strip of cloth against which it rests, and only partway along the top of its other lateral side which 80 extends between said adjacent sections at said seam, said seam forming an offset edge between the top of said lower pocket and the secured portion of the lateral side of said upper pocket which is only partway secured 85 between said adjacent section.

GEORGE W. CARVER.
